UNITED STATES PATENT OFFICE.

JOHN ALEXANDER STRONG, OF CAIN, KANSAS.

BOX-FASTENER.

SPECIFICATION forming part of Letters Patent No. 403,398, dated May 14, 1889.

Application filed February 12, 1889. Serial No. 299,599. (No model.)

To all whom it may concern:

Be it known that I, JOHN ALEXANDER STRONG, of Cain, in the county of Rice and State of Kansas, have invented certain new and useful Improvements in Box-Fasteners; and I do hereby declare that the following is a full, clear, and exact description thereof, reference being had to the accompanying drawings, and to the letters of reference 10 marked thereon, which form part of this specification, in which—

Figure 1 is a perspective view of a crate or box having my improved fastening devices applied. Fig. 2 is a vertical sectional view of 15 the same; Fig. 3, an end view; Fig. 4, a bottom view of the top, and Fig. 5 a view of the opposite end of the box. Figs. 6, 7, and 8 are detail views of the cover-fastening devices.

This invention relates to the fastening devices of the covers of boxes and crates, and is an improvement on the fastening devices shown in my patent, No. 344,875, dated July 6, 1886; and it consists in so constructing the fastening devices that they will be securely 25 protected when the cover is closed, and are not liable to be accidentally knocked open; all of which will be clearly understood from the following description and claims.

Referring by letter to the drawings, A indicates the body of a box or crate composed of 30 sides, bottom and end pieces, and B C are two rectangular castings embracing the end corners and edges of the box, and re-enforcing the latter. The sides and bottom and 35 end pieces may be attached direct to these castings by rivets or screws without otherwise connecting them to each other, and I can thus make a cheap and strong crate. These castings are connected at top by narrow horizontal pieces b c, which project above the tops 40 of the side and end pieces sufficiently to be about flush with the cover when the latter is put in place. The pieces are preferably formed integral with the castings; but instead 45 of casting the pieces and parts B C might be formed of malleable or sheet metal, but are preferably cast for the sake of rigidity.

D represents the cover, which fits on the 50 box between pieces b c and the upper ends of the side flanges of the castings, so that the cover must be lifted directly off the box to

remove it therefrom. Piece b is formed near its lower edge with two or more slots, E E, and has an ear, e, projecting from its center. Piece c is cut away about centrally, as at F; but the 55 adjoining ends of the strip are connected by an ear, f, which is cut or notched at f' adjoining cut F, as shown. On the under surface of cover E, at one end thereof, is secured a transverse strip, G, from the outer edge of 60 which project lugs g g, corresponding in number and position to the slots E E in piece b, and H is a similar strip on the other end of the cover, but not having any lugs.

h is an inclined notch cut in the end of the 65 cover next cut F, as shown.

J designates a spring-catch seated in a recess, I, in the end of the box, to which casting C is attached. The upper end of the catch projects under ear f and moves through 70 cut F, and has an inwardly-projecting latch-head, j, as shown.

The cover is secured by first slipping its end having strip G against piece b, so that lugs g enter slots E. The other end of the cover 75 is then pressed down beside piece c and the head of catch J is pressed back by the edge of strip H until it can spring thereover into notch h. When thus sprung, it is obvious that the catch will hold down that end of the 80 cover unless forcibly drawn outward, while lugs g g are held in piece b. The cover by this means can have no movement at all except with the box. Blows on the outer face of the latch will not disengage or injure it. Pieces 85 b c prevent any prying under the ends of the cover. Ear f, while serving its purpose as a hand-hold, also serves to protect the head of the latch, and as a connection between the separated ends of piece c. The strips G H reinforce the lid, and lugs g are protected from 90 injury by piece b while the cover is closed.

Having thus described my invention, I claim—

1. In a box-fastening, the combination of 95 the piece b, having slots, secured at one end of the box, and the piece c, having a central cut, and an ear, f, connecting the adjoining ends of said piece, and the spring-catch J, having an inwardly-standing latch-head moving in the cut of piece c, with a cover having lugs at one end engaging the slots of piece b,

and a notch at its other end to engage catch J, all substantially as and for the purpose described.

2. The combination of the box, the castings B C, secured to the ends thereof, having pieces b and c, respectively, at their upper sides, piece b being slotted, as described, and piece c cut away at its center and its adjoining ends connected by an ear, f, and the spring 10 catch J, playing through said cut in piece c, with the cover having a transverse strip at one end provided with projecting lugs en-

gaging the slots in piece b, and having a notch and strip at its other end to engage catch J, substantially as and for the purpose 15 specified.

In testimony that I claim the foregoing as my own I affix my signature in presence of two witnesses.

JOHN ALEXANDER STRONG.
